UNITED STATES PATENT OFFICE.

GEORGE H. LOBER, OF TOLEDO, OHIO.

MACHINE FOR FORMING BRASS SPRING STRIPS FOR RADIATORS.

Application filed April 8, 1921. Serial No. 459,766.

To all whom it may concern:

Be it known that I, GEORGE H. LOBER, a citizen of the United States, and a resident of Toledo, in the county of Lucas and 5 State of Ohio, have made an Invention Appertaining to Machine for Forming Brass Spring Strips for Radiators; and I do hereby declare the following to be a full, clear, and exact description of the invention, such 10 as will enable others skilled in the art to which it appertains to make and use the same, reference being had to the accompanying drawings and to the characters of reference marked thereon, which form a part of 15 this specification.

My invention has for its object to provide an efficient machine for forming springs from strips of spring brass whereby transverse corrugations may be successively 20 formed and also whereby the strips may be cut at the proper lengths suitable for assembling in a radiator.

The invention may be contained in structures of different forms. To illustrate a 25 practical application of the invention I have selected a structure containing the invention and shall describe it hereinafter. The structure selected is illustrated in the accompanying drawings.

30 Fig. 1 of the drawings illustrates a front view of the machine selected for purposes of illustration. Fig. 2 illustrates a part of the brass strip operated upon by the machine. Fig. 3 is an end view of a portion 35 of the machine. Fig. 4 illustrates a pair of feeding rolls and shows a section taken on the line 4—4 indicated in Fig. 1. Fig. 5 illustrates a sectional view taken on the line 5—5 indicated in Fig. 4. Fig. 6 shows a 40 side view of a part of the mechanism illustrated in Fig. 4.

In the figures, 1 is the supporting framework of the machine. The machine may be driven by a drive pulley 2 which operates 45 the crank shaft 3 supported in the frame 1. A ram 4 is connected to the crank shaft 3. Dies 5 and 6 are connected to the ram 4 and coact with the die 7 to shape the strips of brass 8 that are fed to the machine from 50 the spools 9. The spools 9 are supported on the bracket 10 secured to the frame 1 of the machine.

The dies 5, 6 and 7 have transverse corrugations conforming to the shape into 55 which the strips 8 are to be formed. The die 5 is connected to the ram 4 by means of

rods 11 that are loosely mounted in the ram 4 to permit a certain amount of free movement of the die 5 relative to the ram 4. The die 5 is yieldingly held away from the 60 ram 4 by means of springs 12 located between the die 5 and the ram 4. The strips 8 are fed across the dies 5, 6 and 7 and the corrugations are formed by the operation of the die 6 coacting with a portion of the 65 die 7. As the strips are further fed above the die 7 the die 5 operates to position the previously formed corrugations with reference to the corrugation that is about to be formed by the die 6. The springs 12 force 70 the previously formed corrugations into certain of the corrugations of the die 7 previous to forming the succeeding corrugations, by the operation of the die 6, since the spring 12 will force the die 5 against the formed portion 75 of the strip and thus force the corrugated portion of the strip into the corrugations of the die 7. The springs 12 operate to hold the strips 8 in position while the ram 4 is moving down and causes the die 80 6 to form the additional corrugation or additional corrugations in the strips 8. When the dies 5 and 6 are lifted the strips are again fed forward into the machine.

The strips are fed into the machine by 85 means of the rollers 13 and 14 that are connected together by the cog wheels 15. The rollers are operated by a ratchet 16 and a dog 17. The ratchet 16 is connected to the shaft of the roller 13 while the dog 17 is located on 90 the arm 18 that is oscillated by the link 19 which is connected to the arm 18 and is also connected to the crank shaft 3 by means of the bell crank lever 25 and the link 26. The rollers 13 and 14 are thus operated in 95 unison with the operations of the ram 4 and they move to feed the strips 8 into the machine when the ram 4 is lifted. The length of the strips 8 that are thus fed successively into the machine may be varied 100 according to the position of the pivot point of connection between the head 20 on the crank shaft 3 and the end of the link 26. The head 20 may be provided with a slot and a pair of overhanging plates 21; and a 105 lug 22 may be adjustably secured in position in the head 20 by means of the bolt 23. The link 26 is pivoted to the lug 22 and is also pivoted on the bolt 23 whereby the head 20 may rotate relative to the link 19 110 and the link 26 may perform transverse oscillatory movement to conform to the

movements of the arm 24 located on the bell crank lever 25. Also the extent of each of the step by step movements of the rollers 13 and 14 may be varied according to the adjustment of the link 19 relative to the arm 27 located on the bell crank lever 25. The extent of the step by step movements where a single corrugation is formed by the die 6 would therefore be such as to feed sufficient amount of the strips to form a single corrugation beneath the die 6.

In order to permit the strips 8 to be drawn forward when the die 6 enters the die 7 to form the corrugations, the rollers 13 and 14 are separated by means of the lever 28 which is pivoted on the frame 29 that supports the rollers 13 and 14 on the frame 1. The lower roller 14 is supported in bearing blocks 30 that are raised by the operation of the springs 31 so as to press the roller 14 against the roller 13. The sides of the frame 29 are provided with rods 50 that extend through holes formed in the sides of the frame and so as to press against the tops of the blocks 30. The rods 50 are pushed down by the plate 32 that forms a part of the lever 28, when the lever 28 is pushed down by the operation of the ram 4 which strikes the head of the adjustable screw 33. When, therefore, the ram has reached a certain position in its downward movement, the lever 28 is forced down which pushes the blocks 30 down against the tension of the compression springs 31 and thus the roller 14 is lowered to release the strips 8 which permits the die 6 to draw the strips forward into the machine.

The strips are severed when sufficient lengths of the corrugations have been formed by means of the plunger 34 which is also operated by the bell crank lever 25. The time of the operation of the plunger 34 is automatically controlled by the machine and so that the plunger 34 is operated after a predetermined number of corrugations have been formed. A link 35 is connected to the bell crank lever 25 and to an arm 36 that is provided with a dog 37 that operates upon the ratchet 38 in substantially the same manner that the ratchet 16 is operated upon by the dog 17. The ratchet 38 is pivotally supported on the frame 1 for rotative movements and as the bell crank lever 25 is operated by the adjustable link 26 the ratchet 38 is rotated. The ratchet 38 is provided with a cam surface 39 which operates upon the end of an arm of the bell crank lever 40 when the cam 39 reaches a certain point in its rotation. The bell crank

lever 40 is pivoted on the frame 1 and operates to draw a sliding rod 41 that is supported in the frame 1. The rod 41 is provided with an arm 42 that operates upon a clutch 43 that causes connection of a ring 44 with the bell crank lever 25. Rotation of the bell crank lever 25 thus causes rotation of the ring 44. A finger 45 is connected to the ring 44 and to the plunger 34. The finger 45 extends through an opening located in the shank of the plunger 34 so that upon the operation of the finger 45 the plunger 34, coacting with an opening 46 formed in the table of the machine, severs the strips 8. This is performed when the plunger is operating through the die 6 to form a corrugation. The plunger 34 and the cooperating opening 46 is preferably so shaped as to cut out pieces of the strips located between the dotted lines 47 indicated in Fig. 2. Therefore the edges of the plunger 34 coact with both side edges of the opening 46 to remove the portions of the strips between the dotted lines 47.

I claim:

1. In a machine for forming strips, a stationary die, a ram, a pair of dies connected to the ram, one of the dies movable relative to the ram, compression springs located intermediate the movable die and the end of the ram for positioning the strips relative to the stationary die and for holding the strips while the other die connected to the ram co-acts with the stationary die to shape the sheet material, a pair of rollers for feeding the strips over the stationary die, and means operated by the ram for releasing the rollers from the strips.

2. In a machine for forming strips, a stationary die, a ram, a pair of dies connected to the ram, one of the dies movable relative to the ram, compression springs located intermediate the movable die and the end of the ram for positioning the strips relative to the stationary die and for holding the strips while the other die connected to the ram co-acts with the stationary die to shape the sheet material, a pair of rollers for feeding the strips over the stationary die, means operated by the ram for releasing the rollers from the strips, a shearing plunger, means interconnecting the said ram and plunger to cause the operation of the shearing plunger after a predetermined number of operations of the ram.

In testimony whereof I have hereunto signed my name to this specification.

GEORGE H. LOBER.
